SHOE STYLE DISPLAY

Charles W. Conaway, Great Neck, N. Y.

Application December 13, 1933, Serial No. 702,145

1 Claim. (Cl. 35—17)

This invention relates to cardlike display devices for demonstrating different shoe styles, and each such device comprises a structure in which the different component parts are so assembled that a profile reproduction of one side of a shoe is provided showing material, trimming, contour and color of each particular style. This invention enables a salesman to equip himself with a large number of such devices for demonstrating a corresponding number of different shoe styles, all of which devices may be packed in small compass and easily transported.

One object of my invention is to produce a device of the character indicated, the construction of which lends itself to economy and speed of production. Another object is to provide a construction which permits of the successful use of the actual materials that are to go into the finished shoe. Another object is to provide a construction whereby the various component parts will be securely held together so as to resist long, rough usage.

Other objects will be manifest to anyone skilled in this art from a reading of the following description and an examination of the accompanying drawing showing my invention in a preferred form, and in which—

Fig. 1 is a front view of the completed display device;

Fig. 2 is a relatively enlarged section on the line 2—2 of Fig. 1;

Fig. 3 is a view of a cardboard blank that constitutes the main body or background of the display card;

Fig. 4 is a view of a second cardboard blank designed to be connected to the blank shown in Fig. 3, which second blank serves as the immediate support for the material or materials that are to go into the shoe to be illustrated.

1 represents what I may term the background blank, preferably made of relatively high-grade cardboard. 2 represents another blank which is preferably made of cardboard especially adapted to take an embossing operation and to effectively retain its shape after such operation. 3 represents a slit in the blank 1, which, in the form shown, follows the outline or profile of the sole, heel, and counter of a shoe to be illustrated. The central portion 2^a of the blank 2 is embossed to simulate in contour one side of such a shoe. On the obverse side of blank 2 is stretched a thin sheet 4, or pieces, preferably of the actual material such as to be used in the shoe, including the heel portion and the trimmings. A suitable adhesive is employed

to secure this material to the surface of the blank 2. The layer 4 may project beyond the edge of the embossed portion 2^a of the blank, no care being required in this operation to see that it terminates at said edge. After the adhesive aforesaid has been fully dried, I trim off (as along the dotted line x—Fig. 4) the surplus material at the upper part of blank 2 so as to properly outline the upper part of a shoe. I then pass the lower and rear edges 2^b of the blank 2 through the slit 3 so as to bring the corresponding edges of the embossure 2^a snugly down to the slit. By the use of a suitable adhesive, I then secure to the back of blank 1 the marginal portion 2^b of the blank 2. Since a relatively broad surface area of engagement is thus afforded, this connection will be exceedingly firm and durable. I may then secure the upper part of the blank 2 to the blank 1 by means of a suitable adhesive. Since the upper part of the blank 2 stands slightly above the surface of the background blank 1, this serves to heighten the perspective effect of the embossure and this may be accentuated by shading applied to the surface of the blank 1 just above the upper edge of blank 2. By making the blank 2 separately from the blank 1, I may employ a tough, coarse, and rough surfaced cardboard best adapted to take and hold an embossure and also to hold the outer layer 4 of material. This construction also permits me to use a relatively high-grade cardboard of any desired thickness for the background blank.

In applying a decorative surface layer 4 to the blank 2, if said layer were applied so as to terminate at the edges of the embossure 2^a it is apparent much skill and care would be required on the part of the operative. Furthermore, if so applied there will be a tendency of the edges to buckle and separate. In my method of manufacture, the decorative outer layer 4 is applied to the blank 2 so as to extend beyond the margins of the embossure, so that even if the edges do buckle or strip, no harm is done, since the upper edges are trimmed off back to the line x, while the lower edges are hidden back of the blank 1, the exposed edge of the slit 3 being relied upon to sharply define the adjacent visible portion of the shoe being demonstrated. As a result of this construction, it is apparent that much time is saved and little skill is required in producing the display devices.

I claim:

A display card for a shoe comprising a background blank having an irregular slit therein

contoured to a portion of the outline of said shoe, a second blank having an embossed portion contoured to the shoe being displayed, a layer of material adhesively secured to the obverse surface of the embossed portion of the second blank simulating the material of the article being displayed, a portion of said layer

extending beyond the embossed portion and secured to the border of said second blank, said border projecting entirely through said slit and secured to the back of said background blank, the shoulder of said embossed portion engaging one edge of said slit.

CHARLES W. CONAWAY.
